UNITED STATES PATENT OFFICE.

PAUL MAUSER, OF OBERNDORF-ON-THE-NECKAR, GERMANY.

TRIGGER MECHANISM FOR AUTOMATIC OR SELF-LOADING SMALL-ARMS.

1,081,761.

Specification of Letters Patent. Patented Dec. 16, 1913.

Application filed October 31, 1911. Serial No. 657,851.

To all whom it may concern:

Be it known that I, PAUL MAUSER, privy commercial councilor, a subject of the King of Wurttemberg, residing at Oberndorf-on-the-Neckar, Germany, have invented certain new and useful Improvements in Trigger Mechanism for Automatic or Self-Loading Small-Arms, of which the following is a full, clear, and exact description.

The invention relates to trigger mechanism for automatic or self loading small arms and essentially consists in the provision of a member which, actuated by the breech piece, disestablishes the engagement of the trigger mechanism when the breech is open.

The accompanying drawing shows the invention by way of example as applied to a Mauser recoil loading pistol with fixed barrel and breech carriage guided on the frame.

In this drawing: Figure 1 shows the loaded and closed weapon in side elevation, partly in longitudinal section. Fig. 2 shows the trigger mechanism at the moment of firing, the breech carriage still occupying the closed position. Fig. 3 shows the fired weapon with the breech carriage in the open position. Figs. 4 to 7 show the trigger mechanism to a larger scale. Fig. 4 is an elevation with the breech closed corresponding to Fig. 1. Fig. 5 is a section on the line 5—5 in Fig. 4. Fig. 6 is a view corresponding to Fig. 3 with the breech open and Fig. 7 is a section on the line 7—7 in Fig. 6.

In the recoil loading pistol illustrated the breech carriage *v* is slidably mounted in the known manner by means of lateral projections along the upper part of the frame *g* which is provided with suitable guides. The handle proper is formed as a magazine casing. On the upper end of this magazine casing the sear lever which is formed as a two-armed lever *a*¹ *a*² is pivoted laterally at *a*. The arm *a*² of the sear lever which is bent inwardly around the magazine casing carries the sear dog *a*³ projecting into the path of the percussion bolt; when the pistol is cocked this dog engages and prevents further movement of the percussion bolt as distinctly shown in Fig. 1. The arm *a*¹ of the sear lever is also bent inwardly around the magazine casing and engages at the nose *c*¹ the dog *c* which is pivoted at *c*² to the trigger *s* and acted upon by the spring *d*.

According to my invention a dog *k* rockable about the pivot *k*¹ is provided above the sear lever, the upper tapered portion *k*² of

this lever being adapted to enter a corresponding recess *v*² in the breech carriage when the breech is closed and its lower nose *k*³ bears on a projection *c*³ formed laterally on the dog *c*.

When the pistol is loaded and properly closed (Fig. 1) and the trigger is actuated the percussion bolt is released in the known manner so that the dog *k* enters the recess *v*² in the breech carriage and therefore does not affect the engagement between the dog *c* and the sear lever *a*¹ *a*². As soon as the breech carriage slides rearward after firing the dog *k* is rotated downward out of the recess *v*² by the inclined face of the recess *v*² of the breech carriage which presses on its upper edge. Its nose *k*³ then presses on the projection *c*³ on the dog *c* whereby the latter is removed from the path of the sear lever *a*¹ *a*². The sear lever is thus released from its engagement with the dog and under the influence of its spring *f* rocks back into its engaging position. The percussion bolt is consequently engaged in the movement of the sear lever dog irrespective of whether the safety device still retains the trigger dog or not. It is only after the breech carriage has returned to the locking position that the dog *k* is able to reenter the recess *v*² and release the dog *c* for engagement with the sear lever.

The improved mechanism therefore fulfills the double function of automatically disestablishing engagement between the dog and the sear lever after firing and of preventing the release of the percussion bolt when the breech is not closed.

What I claim as my invention and desire to secure by Letters Patent of the United States is:

1. The combination with a self-loading small-arm, of a breech carriage and frame, trigger mechanism, a sear lever adapted to engage said trigger mechanism, and a member pivoted to the frame and actuated by the movement of said breech carriage for disestablishing the engagement between said trigger mechanism and said sear lever.

2. The combination with a self-loading small-arm, of a breech carriage and frame, trigger mechanism, a firing pin, a member pivoted to the frame and actuated by said breech carriage and oscillated thereby for rendering the trigger mechanism inoperative when the breech is open, and a sear lever adapted to be disengaged from said

trigger mechanism immediately after firing and to interrupt the reciprocatory movement of and lock the firing pin during the return movement of said breech carriage.

5 3. The combination with a self-loading small-arm, of a breech carriage, a trigger, a dog pivoted to said trigger, a sear lever adapted to engage said dog, and means actuated by said breech carriage and oscillated thereby for disengaging said trigger dog from said sear lever.

10 4. The combination with a self-loading small-arm, of trigger mechanism and a frame, a breech carriage formed with a tapering recess, a sear lever, means for effecting the engagement of said trigger mechanism with said sear lever, and a member pivoted to the frame and actuated by said carriage and adapted to enter said recess for permitting the engagement of said trigger mechanism with said sear lever and to be disengaged from said recess for effecting the disengagement of said trigger mechanism from said sear lever.

15 25 5. The combination with a self-loading small-arm, of trigger mechanism and a frame, a breech carriage formed with a recess, a sear lever, means for effecting the engagement of said trigger mechanism with 30 said sear lever, and an oscillating member pivoted to the frame and actuated by said

breech carriage and adapted to ride on the underside of said carriage to disengage the trigger mechanism from the sear lever when the breech is open and to engage in said recess to permit the engagement of the trigger mechanism with the sear lever when the breech is closed. 35

6. The combination with a self-loading small-arm, of trigger mechanism, a sear lever, a spring adapted to effect the engagement of said trigger mechanism with said sear lever, a breech carriage formed with a recess having a surface gradually inclined to the line of movement of said breech carriage, and an oscillating member actuated by said carriage and having a surface corresponding to the inclined surface of said recess and adapted to engage therewith when the breech is closed for permitting the engagement of the trigger mechanism with the sear lever and to be disengaged therefrom upon the opening of the breech for effecting the disengagement of said trigger mechanism from said sear lever. 40 45 50 55

In testimony whereof I have affixed my signature in presence of two witnesses.

PAUL MAUSER.
